Louis R. Kelley,

BY *J. Stuart Freeman,*

ATTORNEY

INVENTOR

UNITED STATES PATENT OFFICE.

LOUIS R. KELLEY, OF BETHLEHEM, PENNSYLVANIA, ASSIGNOR TO BETHLEHEM FOUNDRY & MACHINE COMPANY, A CORPORATION OF PENNSYLVANIA.

RABBLE AND RABBLE ARM FOR METALLURGICAL FURNACES.

Application filed November 11, 1924. Serial No. 749,120.

To all whom it may concern:

Be it known that I, LOUIS R. KELLEY, a citizen of the United States, residing at Bethlehem, in the county of Northampton and State of Pennsylvania, have invented certain new and useful Improvements in Rabbles and Rabble Arms for Metallurgical Furnaces, of which the following is a specification.

10 The object of the invention is to provide improvements in metallurgical furnaces, and particularly in that type in which a series of hearths, preferably superimposed and in concentric relation with one another, surround a rotatable shaft from which arms extend radially into the chambers between adjacent hearths and carry means known as blades or rabbles that both stir the material and propel it either towards the axis or towards the outer periphery of each of the respective hearths.

Another and more specific object is to provide improvements in the construction of the blade- or rabble-carrying arm used in such furnaces, said arm being provided with a channel through which air passes from within the rotatable hollow supporting shaft to cool the arm and the rabble-blades carried thereby.

30 A further object is to provide an improved rabble which can be removably mounted upon said arm at will and can be readily replaced when broken or mutilated, said rabble being provided with an aperture communicating with the air channel in the arm, and adapted to lead air from said channel outwardly through the rabble to cool the latter, and when desired to unite with gases arising from the material upon the hearth.

40 Still another object is to provide a modified form of rabble, wherein instead of each rabble being provided with an air aperture passing through it, the side of the body portion of each rabble is so shaped as to co-operate with the rabble next adjacent thereto and provide an air passageway from the channel within the arm, for the specified purpose.

50 A modified form of arm may be made with a longitudinally extending transverse partition within the otherwise open channel, so as to provide a pair of parallel channels connected at their adjacent outer end

portions, whereby air from within the hollow shaft (or from pipes within the shaft) 55 passes longitudinally the full length, and beneath the uppermost wall, of the arm, thence into the nether channel and either through or between the blades or rabbles.

With these and other objects in view, the present invention comprises additional novel details of construction and operation hereinafter fully brought out in the following description, when read in conjunction with the accompanying drawings, in which Fig. 1 is a vertical diametrical section of a portion of a furnace in which the invention in its several phases is employed; Fig. 2 is an enlarged, partially fragmentary, detail view of the rabble supporting arm, together with a set of rabbles operatively supported thereby; Fig. 3 is a section on the line 3—3 of Fig. 2; Fig. 4 is a bottom plan view of a fragment of the rabble-arm, showing a pair of the rabbles carried thereby; Fig. 5 is an end elevation of the arm and rabbles; Fig. 6 is a section on the line 6—6 of Fig. 2, but showing a modified form of rabble supported by the arm; and Fig. 7 is a bottom plan view of a portion of the arm and a plurality of the modified form of rabbles carried thereby.

Referring to Fig. 1 of the drawings, a portion of an ore-roasting furnace is shown, the same comprising an outer annular wall 1, from which extend radially inwardly a vertical series of hearths 2 of any desired cross section, and alternate hearths being provided with drop-holes 3, adjacent to their radially inner portions, and intermediate hearths being provided with drop-holes 4 adjacent to their radially outer portions and closely adjacent to the inner surface of the said outer wall 1. The several hearths are provided centrally with axially aligned openings 5, through which extends a vertical hollow shaft 6, to which the rabble or rabble carrying arms are secured.

Referring to Figs. 2 to 5 inclusive, each arm comprises an elongated shell 7, preferably U-shaped in cross-section to provide oppositely disposed sides 8, which in the type shown terminate downwardly in inwardly directed aligned flanges 9, which provide shoulders adapted to support the removable rabbles hereinafter described.

The radially outer end of the shell 7 is closed at 10, while the radially inner end portion comprises a hollow tubular shank 11, separated from the major portion of the shell by means of a peripherally extending shoulder 12, and provided with suitable apertures 13, connecting with a longitudinally extending channel 14, for a purpose hereinafter described.

10 The rabble carrying arm may be mounted upon the shaft 6 in any desired manner, but in this instance is illustrated as extending through apertures 15 in said shaft, and within said shaft being connected with one of 15 the air supply pipes 16, which conveys air into the channel 14 and throughout the longitudinal extent of the arm for cooling the same amidst the high temperature which obtains in the chambers 17, where said arms rotate between the adjacent hearths.

19 In the construction illustrated, each of the improved rabbles or rabble-blades comprises a body portion 18, having oppositely extending lugs 19, adapted to rest and slide upon 25 the shoulders of the flanges 9, each of said rabbles further comprising a depending blade 20, having diagonally disposed surfaces 21 and with an aperture 22 leading from a recess or cavity 23 in the upper surface of the body portion to the lower portion of the rabble, so as to permit air from 30 within the shell 7 of the arm to pass outwardly therefrom and cool the respective rabble-blades.

35 Referring to Figs. 6 and 7, the identical arm is shown as that hereinbefore described, but each of the rabbles comprises a body portion 24, having oppositely extending lugs 25 resting upon the flanges 9, and provided 40 with a depending blade 26, having diagonally directed surfaces 27, but instead of being provided with an air-port, such as in the form previously described, the body portion of each of said rabbles is provided with a 45 cut-away or grooved surface 28 upon either one or both of its opposite sides, so that when an arm is provided with a complete set of rabbles, operatively positioned closely adjacent to one another, the cut-away or 50 grooved surfaces 28 provide openings which permit air from within the hollow arm to pass toward and around the blades 26, with substantially the same result as in the construction first described.

55 In the operation of this device, when the shaft 6 and the arms carried thereby are rotated, the rabbles or arms above one hearth are arranged diagonally in one direction, while the rabble supported by the arms above 60 the hearth immediately therebeneath are arranged in another direction, that is, angularly disposed with respect to the rabbles carried by the arm above, with the result that, as the shaft rotates, the ore upon the 65 upper hearth will be stirred and propel

radially inwardly of the hearth towards the drop-hole 3, whence upon reaching the hearth immediately therebelow, the blades of the rabbles carried by the arms in that immediate chamber stir and propel the ore 70 radially outwardly toward the drop-hole 4, and so on until the ore has passed over the several hearths throughout the entire vertical extent of the furnace.

75 It is also to be understood that the invention in its broad aspect, in addition to the two forms of rabbles herein described, in conjunction with a single form of arm, likewise anticipates the construction of an arm in which the body portion of the rabbles 80 form a side instead of a bottom wall of the air channel of the arm. Similarly, the arm may comprise a suitably reinforced plate or blade, and in which case the body portion of the rabbles would be supported upon the 85 laterally opposite edge portions of the plate or blade, and be angular or U-shaped so as to provide an air channel by and upon the joining of the several rabbles of a set upon the arm.

90 Having thus described my invention, what I claim and desire to protect by Letters Patent of the United States is:

1. The combination of a rabble arm with a plurality of rabble units removably 95 mounted thereon, said arm and the body portion of said units forming, in conjunction, a channelled shell.

2. The combination of a rabble arm with a plurality of rabble units removably 100 mounted thereon, said arm and the body portion of said units forming, in conjunction, a channelled shell, and said units being so formed as to provide a plurality of air outlets from the interior of such shell. 105

3. The combination of a rabble arm with a plurality of rabble units removably 110 mounted thereon, said arm and the body portion of said units forming, in conjunction, a channelled shell, and said units being provided with apertures through their heads.

4. The combination of a hollow rabble arm having a longitudinally extending opening in one of its side walls and a plurality 115 of rabble units removably mounted thereon in such position that their body portions co-operate to close the opening in the wall of said arm.

5. The combination of a hollow rabble arm having a longitudinally extending opening in one of its walls and a plurality of rabble units removably mounted thereon in such position that their body portions co-operate to close the opening in the wall of 125 said arm save for a plurality of air outlets from the interior of said arm between the units.

6. The combination of an arm having a channel opening laterally through one side 130

of the arm, the side walls of the channel being oppositely directed to form supporting flanges, and a plurality of members removably supported by said arm upon said flanges and substantially closing the otherwise open side of the channel.

7. The combination of an arm having a channel opening laterally through one side of the arm, the side walls of the channel being oppositely directed to form supporting

flanges, a plurality of members removably supported by said arm upon said flanges and substantially closing the otherwise open side of the channel, and passageways formed in each of said members to permit air to pass therethrough from within said channel. ¹⁵

In testimony whereof I have affixed my signature.

LOUIS R. KELLEY,
